UNITED STATES PATENT OFFICE.

JAMES H. MORRISON, OF DAYTON, OHIO.

LAMP-BURNER.

No. 827,812.

Specification of Letters Patent.

Patented Aug. 7, 1906.

Application filed April 13, 1906. Serial No. 311,582.

To all whom it may concern:

Be it known that I, JAMES H. MORRISON, a citizen of the United States, residing at Dayton, in the county of Montgomery and State of Ohio, have invented a new and useful Lamp-Burner, of which the following is a specification.

This invention relates to lamp-burners, and has for its object to increase the height and width of the flame of an ordinary burner, and thereby increase its light-power. In this connection it is proposed to employ air-currents for increasing the height of the flame and spreading the same and to produce these air-currents without making any material alteration in ordinary or conventional forms of lamp-burners.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of a lamp-burner embodying the features of the present invention, the bell or hood being open. Fig. 2 is a longitudinal sectional view thereof with the bell or hood closed. Fig. 3 is a top plan view of the burner. Fig. 4 is a detail fragmentary perspective view of a portion of the bell or hood, showing the means for producing one of the air-currents for spreading the flame.

Like characters of reference designate corresponding parts in all of the figures of the drawings.

As in all conventional forms of lamp-burners, the present burner includes a hollow cylindrical base 1, having a reduced externally-threaded cotted portion 2, designed to screw into the threaded burner-opening of the body of the lamp. The usual form of wick-tube 3 pierces the top and bottom of the base and extends a suitable distance above the top thereof. Within the wick-tube there is a conventional form of wick 4, which is fed up and down by means of the usual spur-wheel (not shown) carried by a

rotatable shaft 5, having the ordinary disk-shaped finger-piece 6. Snugly embracing the wick-tube above the body is the usual perforate gallery 7, which is supported from the base by means of arms 8, radiating therefrom and extended to form chimney-holding fingers 9, rising above the top of the gallery. 55 A conventional form of hood or bell 10 embraces the upper projecting portion of the wick-tube and is hinged to the gallery or otherwise removably connected thereto. The top of the hood or bell is provided with the 60 usual diametric slot 11, through which the flame rises. The parts thus far described are common and well known, and therefore may be varied at will, these parts having been shown in the drawings in order that the application and operation of the invention may be adequately understood.

For the purpose of increasing the height of the flame over that of an ordinary burner it is proposed to produce upwardly-directed 75 air-currents at opposite sides of the wick-tube, and this is accomplished by means of upwardly-converged air tubes or passages 12, which pierce the gallery and rise to points adjacent the top of the wick-tube, these 80 draft-tubes being open at their upper and lower ends. A convenient form of draft-tube is produced by means of a metallic plate bent into substantial U shape in cross-section so as to snugly embrace the wick-tube, to 85 which it may be soldered or otherwise rigidly connected, said draft-tube being set obliquely across the wick-tube, so as to produce a relatively large open lower end and a comparatively small open upper end for the purpose of creating a stronger updraft than would be produced by a tube of the same diameter 90 throughout its length.

It will be understood that when the lamp is burning updrafts will be produced through 95 the passages or draft-tubes 12, the tendency of the drafts being to prevent spreading of the flame and to cause the same to become elongated, or higher than with an ordinary burner.

In order that the flame may also be spread out, it is proposed to provide outwardly-directed currents of air at the same sides of the wick-tube as the upwardly-directed currents of air. To accomplish this feature, the hood 100 or bell 10 is provided upon its inner side, ad-

- 2
- 5 jacent each air-tube 12 of the wick, with an air-tube 13, which ordinarily consists of a metal strip connected at opposite ends to the interior walls of the hood, whereby the plate 5 constitutes a chord of the arc of the hood or bell between the ends of the plate, thus producing an upwardly-directed open-ended air-passage defined between the plate 13 and the adjacent wall portion of the bell or hood.
- 10 10 The middle portion of the upper edge of the plate 13 is provided with a pair of substantially V-shaped fingers or projections 14, which extend laterally outward and incline upwardly into engagement with the inner 15 wall of the hood or bell, the opening between the projections or flanges constituting an outlet for the air-passage in close proximity to the adjacent lower end of the slot 11 in the bell or hood. At the lower end of the slot 11 20 there is an outwardly-directed lip or projection 15, bent from the bell or hood and constituting a guide to lead the current of air outwardly. When the burner is lighted, there is an updraft generated in each air-tube 13 of the bell or hood, and as these currents escape upwardly and outwardly through the opposite end portions of the slot 11 they will tend to draw or spread out the flame, which is thereby increased in width, as well 25 as being elongated, by the updrafts through the passages 12.
- 30 It will now be understood that in providing the present improvement no material changes are required in the burner beyond forming openings in the gallery 7 to accommodate the draft-tube 12 and in bending out the lips or flanges 15 at the ends of the slot 11 in the bell or hood. These additions may be 35 very conveniently made and will not increase the cost of the burner, while at the same time will materially increase the light-power. It is also proposed to provide for the double feed of oil through the wick, and this is 40 accomplished by folding the lower end portion of the wick upwardly and passing the same through a loop or clip 16, provided upon the bottom of the body of the burner at one side of the open lower end of the wick-tube, whereby the wick will be held in two 45 plies and the supply of oil to the upper burning end of the wick will be materially increased. By preference the loop or clip 16 is formed of wire bent into a substantially L-shaped clip, having its upstanding member 50 soldered or otherwise rigidly secured to the bottom of the base and its under horizontal member or arm lying in substantial parallelism with and at one side of the open lower end of the wick-tube.
- 55 60 In addition to increasing the light the draft-tubes maintain the wick-tube in a relatively cool condition, and the burning of the wick is thereby retarded, which prolongs the

life of the wick. Moreover, the top of each tube 13 terminates short of the top of the wick-tube, as experiments have shown that better results are obtained by this relation of parts, particularly as it maintains the wick-tube relatively cool, and thereby prevents burning of the tube.

Having thus described the invention, what is claimed is—

1. A lamp-burner comprising a wick-tube and a hood, in combination with upwardly-directing air-tubes arranged at the opposite narrow sides of the wick-tube, and means carried by the hood to direct currents of air upwardly and outwardly to spread the flame.

2. A lamp-burner comprising a wick-tube and a hood, in combination with means arranged to produce an upwardly-directed current of air along the wick-tube at the ends of the flame for increasing the height of the latter, and means carried by the hood to produce currents of air directed to spread the flame.

3. A lamp-burner comprising a wick-tube, a hood having a slot above the upper end of the tube for the flame, diverging members extending through the slot at the ends thereof and upwardly-directing air-tubes carried by the wick-tube at the opposite narrow sides thereof for increasing the height of the flame.

4. A lamp-burner having a wick-tube, a hood provided with a slot for the outlet of the flame, and means carried by the hood for producing upwardly and outwardly directed currents of air at opposite sides of the wick-tube for spreading the flame.

5. A lamp-burner having a wick-tube, a hood provided with a slot for the passage of the flame, upwardly-directed air-tubes carried by the wick-tube for increasing the height of the flame, air-tubes carried by the hood, and means associated with the latter tubes for directing currents of air therefrom upwardly and outwardly to spread the flame.

6. A lamp-burner having a pair of plates folded into substantial U shape and embracing opposite narrow sides of the wick-tube to form upwardly-directed air-passages which deliver the air-currents to the ends of the flame, each plate being disposed obliquely across the wick-tube to give the air-tube an upward taper.

7. A lamp-burner having a wick-tube, a hood having a slot for the passage of the flame, outwardly-directed and upwardly-inclined lips extending from opposite ends of the slot in the hood, and upwardly-directed air-passages carried by the hood and leading to the respective ends of the slot in the hood.

8. A lamp-burner having a wick-tube, a hood provided with a slot for the passage of the flame, portions of the hood being bent outwardly at the ends of the slot, and plates

applied to the inner walls of the hood across
the ends of the slot with their terminals con-
nected to the hood and their intermediate
portions spaced therefrom to form open-
ended air-passages leading to the ends of the
slot.

In testimony that I claim the foregoing as

my own I have hereto affixed my signature
in the presence of two witnesses.
